(57)

CLAIMThe ornamental design for a ceiling fan light kit, as shown
and described.**DESCRIPTION**FIG. 1 is a bottom perspective view of a ceiling fan light kit
showing my new design, shown in the environment of a
ceiling fan;FIG. 2 is a top perspective view of the ceiling fast light kit
of FIG. 1, but shown without the ceiling fan environment;
FIG. 3 is a top view thereof;

FIG. 4 is a bottom view thereof; and,

FIG. 5 is a front side view thereof, with rear, right, and left
side views being mirror images thereof.The broken lines shown in FIG. 1 illustrate environmental
structure and form no part of the claimed design.**1 Claim, 5 Drawing Sheets**(56)
